UNITED STATES PATENT OFFICE.

ANDREW J. LOW, OF GERMAN TOWNSHIP, PENNSYLVANIA.

IMPROVED PORTABLE APPARATUS FOR EVAPORATING SACCHARINE JUICES.

Specification forming part of Letters Patent No. 35,830, dated July 15, 1862.

To all whom it may concern:

Be it known that I, ANDREW J. LOW, of German Township, in the county of Fayette and State of Pennsylvania, have invented a new and Improved Portable Evaporating Apparatus; and I do hereby declare that the following is a full, clear, and exact description of the same, reference being had to the accompanying drawings, making a part of this specification, in which—

Figure 1 is a perspective view of my improved apparatus, and Fig. 2 is a vertical longitudinal section of the same, the section being taken through the middle.

Similar letters of reference indicate corresponding parts in the two figures.

This invention consists in an arrangement of devices whereby the operation of removing the scum from the surface of the liquor is greatly facilitated; also, in a device for varying the inclination of the evaporating-pan.

To enable others skilled in the art to fully understand and use my invention, I will proceed to describe its construction and operation.

A represents a furnace, which is mounted on two wheels, B B, placed on each side, behind the grate C, which extends from the front end of the furnace to the offset a, from which to its back end the furnace is gradually decreased in depth by an inclined bottom, b, which, with the sides and bottom of the pan, forms a flue to conduct the unconsumed gases of combustion into the chimney C at the back end of the furnace.

c is a fire-door in the front end of the furnace.

D is a square socket attached to the back end of the furnace by two bars, d d', which embrace the sides of the furnace, and are fastened thereto by rivets or in any other suitable manner.

E is a tongue or draft-pole, fitted at one end in the socket D, and fastened therein by a screw, F, which passes through both socket and tongue. This screw F is provided at its lower end with a swiveled foot, G, and at its upper end terminates in a winch, H, by means of which latter the screw may be rotated, and the back end of the furnace raised or lowered, and consequently the inclination of the evaporating-pan varied, as may be desired, to accelerate or retard the flow of liquor from one division or compartment of the pan to another.

I is an evaporating-pan, divided in the several compartments, K L M N O P; and provided at its front end or in the compartment K

with an inclined plane, J, ending at top in a trough, e, which extends the whole width of the pan and is slightly inclined.

f is a pipe leading from the lowermost end of the trough e, where it is covered with a strainer, g, into the front compartment or receiver, K, of the evaporating-pan I. The evaporating-pan I at its front end is considerably wider than the furnace, and is so placed on it as to project in front and equally over its side. The back end of the pan I, for the width of three pans on one side and two on the other, exactly corresponds in width with the furnace. The compartments of the pan I communicate with each other through openings made alternately in the ends of the partitions h, which openings are closed by sliding gates J. The front compartment or receiver, K, is about equal in capacity to the three succeeding compartments L M N. The last compartment, P, in which the finishing process takes place, is separated from the direct action of the fire by a plate, i, and it is provided in one end with a faucet, k, through which the finished article is drawn off.

The operation is as follows: The evaporating-pan being placed in a proper position and fire started in the furnace, the raw juice is placed in the compartment or receiver K, where it is allowed to remain at a temperature of about 212° Fahrenheit—a sufficient length of time to allow a greater portion of the impurities to rise to the surface of the liquor in the form of scum. This scum, by the action of the liquor in ebullition, is forced toward the inclined plane J, where the liquor, not being of the fire in the furnace, is less agitated. The scum collected together at the foot of the inclined plane is drawn up it by a skimmer of any suitable form and deposited into the inclined trough e. Any juice accidentally skimmed up with the scum passes through the strainer and is returned into the compartment through the pipe f. The scum being removed from the surface of the liquor in the first compartment or receiver K, the gate j, opening in the succeeding compartment L, is raised and the liquor allowed to run therein, and the process of evaporation continued. The first compartment or receiver K is then refilled with crude juice, and the same operation gone through as before. The liquor, after remaining a certain length of time in the compartment L and undergoing the process of evaporation,

is let into the succeeding compartment and at proper intervals thereafter into each succeeding compartment, undergoing in each a partial evaporation until reaching the last compartment, when the process is completed and the finished article drawn off through the faucet. As each compartment is emptied of its evaporated liquor, that of the preceding compartment is let in to take its place. The heat under the several divisions or compartments of the evaporating-pan gradually decreases in intensity from the receiver to the finishing-compartment, the latter being protected from the direct action of the fire by a metal plate.

Having thus described my invention, what

I claim as new, and desire to secure by Letters Patent, is—

1. The receiver K, inclined plane J, in combination with the trough e, strainer g, and pipe f, when arranged to operate in the manner and for the purpose set forth.

2. The screw F, winch H, and swiveled foot G, in combination with the evaporating-pan I and wheels B B, when arranged to operate in the manner specified.

ANDREW J. LOW.
